UNITED STATES PATENT OFFICE.

EDMUND LICHTENSTEIN, OF BERLIN, GERMANY, ASSIGNOR TO DEUTSCHE MASCHINENBAU- UND VERTRIEBS-GESELLSCHAFT M. B. H., OF BERLIN, GERMANY, A FIRM.

DUPLICATOR.

Application filed September 26, 1925, Serial No. 58,908, and in Germany October 16, 1924.

This invention relates to duplicators more particularly applicable for office purposes, which operate on the off-set principle, in that they print from a form cylinder or roller, preferably carrying a thin pliant metal printing form according to German Patent No. 350,484, on to a rubber cylinder or roller and from the latter on to the paper supported by a printing cylinder, roller or the like.

In such office duplicators wherein, as a rule, only a comparatively small number of copies are printed from a printing form, so that a frequent changing of the printing form is necessary, a considerable disadvantage resides in that the frequent removal of the ink still remaining from the previous text from the rubber cylinder, is difficult owing to the fact that even in the most convenient arrangements the rubber cylinder, is located more or less inaccessible underneath the impression and printing cylinders.

According to the present invention this drawback is eliminated whilst retaining the cylinder arrangement above referred to, in that the position of one of the three cylinders of the machine above referred to may be changed in such a manner that the rubber cylinder becomes readily accessible.

In such duplicators the impression cylinder is, as a rule, provided on its periphery with a groove or the like for clamping the pliant printing form thereon, and usually the rubber cylinder is also provided with similar securing means for securing its divided covering consisting of a rubber plate placed around it. These securing means on the impression cylinder and on the rubber cylinder must always pass opposite one another during rotation of the cylinders when the machine is in operation, and when the duplicator prints on a web of paper which is automatically cut into sheets after being printed, the cut must always be effected at the point of the paper exactly corresponding with these securing means.

According to the invention precautions are provided in order that not only when releasing, as is well known in the case of machines without cutting mechanism, but also when the movable cylinder is moved, withdrawn, or the like to a relatively large extent, and when rotating the rubber cylinder for the purpose of cleaning, the operative en-

gagement is retained so that this accurate 55 co-operation is not affected.

In order that the invention may be more clearly understood and readily carried into effect reference may now be had to the accompanying drawings in which examples of 60 construction are shown diagrammatically and in which:—

Fig. 1 is a side elevation of the main parts of a duplicator.

Fig. 2 is a side elevational view illustrating the movement of one of the rollers.

Fig. 3 is a similar view of a modified arrangement.

Fig. 4 is a perspective view of the rollers according to Fig. 1.

Fig. 5 is a similar perspective view showing the driving arrangement for the rollers.

Fig. 6 is a similar perspective view showing a support for the movable cylinder.

Fig. 7 is a perspective view showing a 75 tensioning device.

The machine is provided with a printing cylinder or roller *a*, a rubber cylinder or roller *b* and an impression cylinder or roller *c*. The paper *d* passes from a supply roll 80 between the cylinders *b* and *c*, over the cylinder *c*, under a weighting roller *e* and through the cutters *f* to the delivery device.

The printing cylinder co-operates with a moistening device consisting, for example, of two rollers *g*, and an inking mechanism consisting, for example, of four rollers *h*.

According to the invention the rubber cylinder *b* (Fig. 2) is carried by an oscillatory frame *i* adapted to swing about the axis of the printing cylinder *a* so that the cylinder *b* can be swung from the full line position into the dotted line position in which it can be locked in any suitable manner. In this position the rubber cylinder *b* is freely exposed so that the text or ink from the previous printing operation can be conveniently removed therefrom.

In the construction according to Fig. 3 the position of the printing cylinder *a* is adapted to be changed instead of that of the rubber cylinder *b*. The dotted line in Figure 3 shows the printing cylinder in the operative position in which it leaves the rubber cylinder *b* more or less inaccessible. If, however, the cylinder *a* is moved or swung into the full line position the cylinder *b* becomes accessible.

The machine is driven from the cylinder *a* which by means of the toothed wheels *k*, *l* and *m* drives the cylinder *c* and by means of the toothed wheels *h*, *i* the cylinder *b*.

5 If the cylinder *b* is moved from the full line position in Fig. 2 into the dotted line position the toothed wheels *h* and *i* remain in engagement so that the accurate co-operation, above referred to, between the securing 10 means of the cylinder coverings and the cutting device 4 is retained, the latter being adapted to be positively coupled to the main drive in any suitable manner.

For the purpose of tightening or for producing the operative pressure between the cylinders play is provided in their bearings and is compensated for by a tensioning device. For this purpose, according to the invention only so much play *g* is allowed by 15 20 longitudinal holes, by reason of the mounting of the frame *e* on the axis of the cylinder *a*, that, when loosening, the toothed wheels *h* and *i* cannot be disengaged from one another.

25 As the drive of the rubber cylinder *b* from the printing cylinder *a* is effected by means of the tooth wheel gear *h*, *i*, which is independent of the tooth wheel gear *k*, *l* and *m* driving the impression cylinder *c* and the cutting mechanism 4, the cutting mechanism 30 4 cannot be brought out of step by moving the rubber cylinder in and out.

The frame *e* is held in the operative position by supporting levers *p* which engage 35 under the ends of the shaft of the cylinder *b* and are supported by a shaft *q* which is adapted to be raised and lowered by the tensioning device to be hereinafter described.

These supporting levers, according to the 40 invention, are also used for automatically catching or arresting the cylinder *b* when it swings from the dotted position shown in Fig. 2 back into the full line position. For this purpose the levers *p* are not rigidly 45 clamped on the shaft *q* but are adapted to have a limited yielding movement in a clockwise direction (Fig. 6) in the manner of the known slip pawls. If therefore on the return movement of the cylinder *b* the stub 50 shafts thereof abut against the levers *p* from the rear (left) these yield and move into the dotted position shown in Fig. 6 whereupon, by means of springs not shown, they immediately swing back under the axis of the 55 cylinder *b* into the full line position and now retain the cylinder.

It will be understood that the levers *p* could also be keyed to the shaft *q* which would then have to be spring actuated. Naturally 60 separate catch members could be used instead of the levers *p*.

In order that when moving the cylinder *b* about the cylinder *a* preparatory to printing—particularly when inking the printing 65 cylinder and rotating the corresponding

roller group—paper is not fed and cut uselessly, a releasable clutch *n* is interposed, according to the invention, as shown in Fig. 7, between the roller *a* which has already been designated as the driving roller, and the 70 train of gears beginning with the gear *k* which controls the operation of the paper feed-mechanism and the impression cylinder.

In order that the correct co-operation will not be affected in spite of this only a single 75 hole *r* is provided in the toothed wheel *k* for the coupling pin *n* which couples the cylinder *a* to the toothed wheel *k*. When the pin engages with this hole the correct angular relation of the cylinder is obtained. 80

The coupling pin *n* is controlled by a stationary pusher *s* and may also be spring actuated so that when coincident with the hole *r* it will engage therewith automatically.

According to the invention provision is 85 made so that the proper yielding working pressure between the cylinders is effected automatically as soon as the clutch *n* is engaged. For this purpose a cam *t*, for example, is provided which is positively driven 90 by the toothed wheel *m*, and, as soon as this occurs the pressure lever *u* (Fig. 7) swings in a clockwise direction. The pin *o* of the lever *u* then presses the shaft *q* and thus the cylinder *b* upwardly until the lever *u* is 95 locked in the adjusted position by the catch *v*.

It will be understood that both ends of the shaft *q* are raised uniformly for which purpose a second lever *u* or transmission gear may be provided. 100

For adjusting the necessary pressure of the cylinder to be raised into position without additional trouble and to provide for this pressure also in the case of wear, the pressure pin *o* is actuated by a tension spring *w*. 105

What I claim is:—

1. A duplicator operating upon the offset principle comprising an impression cylinder, a printing cylinder, a rubber cylinder located beneath said first mentioned cylinders 110 when the machine is in operation, said cylinders being operatively connected by toothed gearing, means whereby one of said cylinders may be moved to facilitate access to said rubber cylinder, a cutting mechanism, means for permitting play between the axes of said cylinders, means for taking up this play, the amount of said play being of limited extent so that said toothed gear connection between said cylinders is maintained 115 even when said means for taking up said play is released and means whereby the toothed wheel connection is also maintained when effecting the movement which renders the rubber cylinder conveniently accessible. 120

2. A duplicator operating upon the offset principle comprising an impression cylinder, a printing cylinder, a rubber cylinder located beneath said first mentioned cylinders when the machine is in operation, said im- 130

pression and rubber cylinders being operatively connected by toothed gearing, means including a frame rotatably mounted about the axis of one of the cylinders and carrying another of said cylinders for rendering said rubber cylinder accessible, a cutting mechanism, means on said frame for permitting play between the axis of the cylinder carried by said frame and its associated cylinder, means for taking up said play, the amount of said play being of limited extent so that the toothed gear connection between said movable cylinder and its associated cylinder is maintained even when said means for taking up said play is released and means whereby the toothed gear connection is also maintained when effecting the movement which renders the rubber cylinder accessible.

3. A duplicator operating upon the offset principle comprising an impression cylinder, a printing cylinder, and a driving connection therebetween a rubber cylinder located beneath said first mentioned cylinders when the machine is in operation, means whereby one of said cylinders may be moved so that the rubber cylinder is made conveniently accessible and means for driving said movable cylinder from its associated cylinder independently of the drive between said last mentioned cylinder and the other cylinder whereby a determined relative arrangement between the other cylinders is maintained when the movable cylinder carried by said frame is moved.

35 4. A duplicator operating upon the offset principle comprising an impression cylinder, a printing cylinder, and a driving connection therebetween a rubber cylinder located beneath said first mentioned cylinders when the machine is in operation, means including a frame rotatably mounted about the axis of one of the cylinders and carrying another of said cylinders and a gear wheel connection between said last mentioned cylinders which is independent of the drive connection between the other cylinders whereby a determined relative positioning is maintained between the other cylinders when the movable cylinder carried by said frame is moved.

5. A duplicator operating upon the offset principle comprising an impression cylinder, a printing cylinder, and a driving connection therebetween a rubber cylinder located beneath said first mentioned cylinders when the machine is in operation, means whereby one of said cylinders may be swung about another cylinder to facilitate access to said rubber cylinder, a toothed gear connection between the cylinder that is swung and the cylinder about which it is swung independent of the drive between last mentioned cylinder and the impression cylinder, a cutting mechanism, means for permitting play between the axes of said cylinder that is swung

and its associated cylinder, a device for taking up said play, the amount of play being such that said toothed gear connection is maintained even when said device for taking up said play is released and when effecting the movement which renders the rubber cylinder conveniently accessible.

6. A duplicator operating upon the offset principle comprising an impression cylinder, a printing cylinder, and a driving connection therebetween a rubber cylinder located beneath said first mentioned cylinders when the machine is in operation, means including a frame rotatably mounted about the axis of one of the cylinders and carrying another of said cylinders, a toothed gear connection between the cylinder carried by the frame and the cylinder about which it swings independent of the drive between the last named cylinder and the impression cylinder, a cutting mechanism, means on said frame for permitting play between the axis of said swingable cylinder and its associated cylinder, means for taking up said play, the amount of play being such that said toothed gear connection is maintained even when said means for taking up said play is released and means whereby said connection is also maintained when effecting the movement which renders the rubber cylinder accessible.

7. A duplicator operating upon the offset principle comprising an impression cylinder, a printing cylinder, a rubber cylinder located beneath said first mentioned cylinders when the machine is in operation, means whereby one of said cylinders may be moved to facilitate access to said rubber cylinder, a cutting mechanism, means for permitting play between said movable cylinder and its associated cylinder means for taking up said play, a toothed gear connection between said last mentioned cylinders maintained in engagement even when said means for taking up said play is released, and when the movable cylinder is moved to give access to the rubber cylinder, levers for supporting the movable cylinder and means for causing said levers to bring said cylinder into operative association with its associated cylinder.

8. A duplicator operating upon the offset principle comprising an impression cylinder, a printing cylinder, a rubber cylinder located beneath said first mentioned cylinders when the machine is in operation, means whereby one of said cylinders may be moved so that the rubber cylinder is conveniently accessible and means for automatically latching said movable cylinder adjacent its operative position prior to its being moved into operative relation with its associated cylinder.

9. A duplicator operating upon the offset principle comprising an impression cylinder

der, a printing cylinder, a rubber cylinder located beneath said first mentioned cylinders when the machine is in operation, means including a frame rotatably mounted about the axis of one of said cylinders and carrying another of said cylinders for moving said last mentioned cylinder to facilitate access to said rubber cylinder and means for automatically latching said frame with the 10 movable cylinder adjacent its operative position.

10. A duplicator operating upon the offset principle comprising an impression cylinder, a printing cylinder, a rubber cylinder located beneath said first mentioned cylinders when the machine is in operation, means permitting movement of one of said cylinders to facilitate access to the rubber cylinder, a gear connection between said movable cylinder and one of said other cylinders which is independent of the gear connection between said other cylinder and the remaining cylinder and a releasable clutch interposed in said last mentioned gear connection.

11. A duplicator operating upon the offset principle comprising an impression cylinder, a printing cylinder, a rubber cylinder located beneath said first mentioned cylinders when the machine is in operation, means permitting movement of one of said cyl-

inders to facilitate access to the rubber cylinder, a gear connection between said movable cylinder and one of said other cylinders which is independent of a gear connection 35 between said other cylinder and the remaining cylinder and a releasable clutch which can only engage in a single determined relative rotary position of the impression cylinder and rubber cylinder interposed in said 40 last mentioned gear connection.

12. A duplicator operating upon the offset principle comprising an impression cylinder, a printing cylinder, a rubber cylinder located beneath said first mentioned cylinders 45 when the machine is in operation, means permitting movement of one of said cylinders to facilitate access to said rubber cylinder, a gear connection between said movable cylinder and one of said other cylinders 50 which is independent of a gear connection between said other cylinder and the remaining cylinder, a clutch device in said second mentioned gear connection means for tensioning or moving said movable cylinder 55 into operative association with its associated cylinder and means for automatically tensioning the movable cylinder as soon as the clutch device is engaged.

In testimony whereof I have affixed my 60 signature.

EDMUND LICHTENSTEIN
